his ATTORNEY.

UNITED STATES PATENT OFFICE.

LOUIS BROEMEL, OF SOUTHBURY, CONNECTICUT.

DESIGN FOR A MACHINE-STANDARD.

53,432.

Specification for Design.

Patented June 17, 1919.

Application filed March 1, 1917. Serial No. 151,857. Term of patent 14 years.

To all whom it may concern:

Be it known that I, LOUIS BROEMEL, a citizen of the United States, and a resident of Southbury, in the county of Hartford, State of Connecticut, have invented a new, original, and ornamental Design for a Machine-Standard, of which the following is a specification, reference being had to the accompanying drawing, forming part hereof.

The drawing shows a perspective view of the machine standard.

I claim:

The ornamental design for a machine standard as shown.

LOUIS BROEMEL.

Witnesses:

L. W. REYNOLDS,

L. C. STAHTHORN.
